UNITED STATES PATENT OFFICE.

NELS BERNHARD ANDERSON, OF BELLINGHAM, WASHINGTON, ASSIGNOR OF FOUR-FIFTHS TO EVERETT B. DEMING, OF BELLINGHAM, WASHINGTON.

FISH-CLEANING MACHINE.

1,137,448.

Specification of Letters Patent. Patented Apr. 27, 1915.

Application filed November 2, 1914. Serial No. 869,998.

To all whom it may concern:

Be it known that I, NELS BERNHARD ANDERSON, a subject of the King of Norway, (who has taken out his first citizenship papers 5 in the United States,) and resident of the city of Bellingham, Whatcom county, Washington, have invented certain new and useful Improvements in Fish-Cleaning Machines, of which the following is a specification.

10 My invention relates to fish cleaning machines, and consists in an attachment for a certain type of such machines which will contribute to the better and more perfect working of other parts of the machine and therefore 15 a more thorough cleaning of the fish.

The object of my invention is to thoroughly and effectually remove the bones lying at the base of and which serve as the support and attachment for the anal fin, 20 and also the more effectual removal of the intestine which is directly connected with the rectal opening.

The object in the removal of these parts 25 and the final object aimed at by my invention, is to place the fish in condition such as will cause, or permit, the other and following mechanisms to act more perfectly thereon, thus increasing the efficiency of the following mechanisms and the thoroughness of 30 their work.

My invention comprises the parts and combinations of parts which will be herein-after described and particularly indicated by the claims.

35 In the accompanying drawings I have shown my invention, and in the following specification will describe it, in the form of construction which is now preferred by me.

Figure 1 is a side elevation of a machine 40 of a type with which my attachment and improvement is intended to work, my device being shown applied thereto. Fig. 2 is a detail view of my attachment, the point of view being the same as that of Fig. 1. Fig.

45 Fig. 3 is a plan view of the attachment with only sufficient of the main machine shown to indicate its relationship thereto. Fig. 4 is an elevation of the same parts, but from a direction at right angles to that of Fig. 3. Fig.

50 Fig. 5 is an edge view of the pair of cutter blades, pair of arms being cut away. Fig. 6 is an end view of the cutting ends of one pair of cutting blades, illustrating the method of their engagement with the bones referred to. Fig. 7 is a view of the cutter blades and

the associated shoes, the latter being of a modified construction, the line of view being parallel the rotative axis of the blades. Fig. 8 is an elevation in partial section of the same construction of shoes and their supports, the line of view being at right angles to that of Fig. 7. Fig. 9 is a plan view of the same type of shoe and its supports. Fig. 10 is a cross sectional view of a fish taken through the abdominal cavity. Fig. 11 is a section through the fish and the bones at the base of the anal fin which it is desired to remove.

My invention is designed as an attachment to and improvement upon fish cleaning machines which receive the fish and convey it through a definite path, during which progress it is acted upon by a variety of devices, each performing its particular step in a process of cleaning and preparing the fish 75 for use. One type of construction of such a machine has been shown in Fig. 1, and my device, as herein shown, has been proportioned to fit this machine. It is however, clear that the same mechanisms might be attached to and fitted for other machines, this adaptation for other constructions of machines being merely the function of a mechanic and not affecting the central principles of my invention. The type of machine 80 shown is that which, in the trade, is known as the "Iron Chink," the same being made under patents issued to Smith, Nos. 796,538, 998,129, and 1,034,525. The central structural features of this machine consist in the 85 use of two spaced, revolving rings, A, which are provided with means for holding the fish between their peripheral edges and carrying the fish through a definite circular path, during which movement the fish is acted 90 upon by a series of attachments which each perform their special part in the operation of cleaning the fish. My invention consists of an attachment for such a machine, designed to accomplish a result which the present devices do not accomplish, this result contributing very materially to the perfection of the action of the attachments which come after it in the cleaning process. The operations first performed 95 by such a machine consist in the removal of the head, tail and fins, after which the fish is slit lengthwise so as to open the abdominal cavity and is then operated upon my mechanisms designed to remove the intestines and 100

105 110

the blood which forms a clot along and just under the backbone. It has been found by experience, that these latter mechanisms will not act with certainty and exactness sufficient to insure the satisfactory cleaning of the fish, which makes it necessary to employ a number of operatives to act upon the fish after they leave the machine.

One of the most fruitful causes of this imperfect action of the later mechanisms is as follows: The slitting open of the abdominal cavity is done by a circular cutter or saw, which is located at B. To cut deep enough to insure opening of this cavity, the saw must also cut through a part of the fish body lying back of the rectal opening. Immediately to the rear of the rectal opening is a fin which is called the anal fin. This fin, like others, is secured to or based upon a series of bones which extend from the under surface of the fish inward well toward the backbone. These bones are located exactly upon the center line of the fish, which is the line upon which the slit in the abdominal cavity should be made. As these bones are much more resistant to cutting than the flesh at their sides, they very commonly divert the fish's abdomen to one side, sometimes sufficient to locate the slit half an inch or more from the exact central plane. As the abdomen of a fish is soft and very yielding, it takes but little to divert it from the proper place and, once diverted, the tendency is to increase the diversion. The result of this improper location of the cut through the fish belly, is that the cleaning mechanisms which act later upon the fish, cannot perfectly remove all the offal and this must be done by hand. To cure these defects I have provided an attachment which acts upon the fish before the slitting saw and which removes these bones which lie at the base of the anal fin, thereby removing the chief cause of the trouble and making it possible for the later acting mechanisms to do their work more perfectly. In the removal of these bones the abdominal cavity is slightly extended rearwardly, thereby making it more easy for the cleaning mechanisms to enter and remove the viscera. This would otherwise be more difficult of accomplishment, because of the fact that the outline of the upper margin of this cavity turns downward to the anus, thus making a bend into which it is difficult for the cleaning mechanism to make a perfect entry.

In Figs. 2, 3 and 4, I have shown my attachment by different views, these showing only enough of the parts of the old machine to indicate the relationship of the attachment thereto. The position occupied by the attachment upon the machine is shown at C in Fig. 1. This follows after the knives which remove the tail and fins and precedes the abdominal slitter. My attachment is

mounted upon a pivot axis or frame member, 1, which is located at one side of and substantially parallel the path of movement of the fish. As herein shown this shaft 1 is directly secured to the machine frame by clamps 10 which bind it to posts 11. The shaft 1 might, however, be limited in function to that of serving solely as a pivot, a special frame being employed to support it from the frame of the machine. A frame 2 is pivoted by arms 20 upon the pivot axis 1, and extends transversely of said axis toward the path of travel of the fish. This path is determined by the movement of the drums or rings A, between the edges of which the fish is held. Journaled in frame 2 is a shaft 3, having a bevel gear 30 secured to it at the pivoted end of the frame, this gear meshing with a companion gear 12 journaled upon the pivot axis 1. Secured to the bevel gear 12, is a spur gear 13, which meshes with another spur gear 14, which is secured to an auxiliary or driving shaft 4. Auxiliary shaft 4 is journaled in a frame 40, which has ears 41, 42, which span the pivot axis 1, upon which axis it is thereby pivoted. These ears are also intended as means for clamping the auxiliary frame 40 in adjusted position. I have shown these ears as being provided with bolts 43, by tightening which, the ears may be fixedly secured in place. The shaft 4 may be driven in any convenient and suitable manner. The means shown consists in a sprocket wheel 44, over which is placed a chain 45, which is driven from a wheel mounted upon an overhead shaft of the machine. The swinging end of the shaft 3, has secured thereto a revolving cutter, so as to lie in the plane of movement of the fish. This cutter is composed of a series of blades or knives 5, which are arranged in pairs, those of each pair being placed opposite each other. The outer ends of these knives are bent inward, or toward each other, forming curved ends 50, having their end edges sharpened and also inclined, so as to form a V-shaped opening between them. The forward side edges of these knives are also sharpened for a distance from their ends. The rear end, or apex, of the V-shaped opening between the end cutting edges, are separated but slightly, as is seen in Fig. 6. Between these is shown, at 54, a circle representing the size of one of the bones at the base of the anal fin, which bones it is desired to remove. The separation of the knives at this point should be less than the thickness of these bones, so that they will be either cut off or pulled out. Mounted upon the outer end of the frame 2, is a shoe or shoes 6, placed so as to engage the fish and raise the swinging end of the frame so that the cutter blades will not cut beyond a fixed depth. As shown in Figs. 2, 3 and 4, these shoes are supported by yoke-

like pieces 60, which are secured to the side faces of the outer end 21 of the frame and have legs extending down at each side the cutter to support the shoes 6. These yokes 5 may be provided with slots for the securing bolts 61, whereby the shoes may be vertically adjusted.

In Figs. 7, 8 and 9, a different supporting mechanism for the shoes is shown. This 10 consists of a U-shaped frame, composed of two bars 7, to which the shoes are secured, a connecting bar 70 and a flange 71 which is provided with a vertical slot 75, for the reception of a securing bolt 74, and a transverse slot 72, for the reception of the other securing bolt 76. This member is secured 15 against the outer end face of the cutter carrying frame 2. It may be swung upon the lower bolt 74 to adjust the angle of the 20 under surface of the shoes, and moved bodily up or down to vary its height. I have also shown means whereby the cutter carrying frame may be raised at the times desired by 25 a positive mechanism. In this I secure a cam ring 8, against the outer face of one of the drums or ring frames A, and mount an arm 80 by a pivot 81, supported in ears 22, forming a part of the frame 2. On the lower 30 end of arm 80, is journaled a roller 82, which runs upon the cam ring 8. This roller may be provided with a side flange, 83, which will prevent movement of the roller inward. The roller is held gently inward by a spring, 35 as 23, which is coiled about an extension of the pivot 81 and has one end engaging the ear 22 and the other end engaging a pin 84, carried by arm 80. In operation, the cutter 40 blades will engage the fish at, or just to the rear, of the anal fin, and will cut a groove extending past the anus and making a slight opening into the abdominal cavity. The 45 shoes act to prevent cutting this groove too deep. It will, however, be deep enough to remove the group of bones which extend inward and from which the anal fin is supported, thus removing the main cause for 50 diverting the slitting saw from the central line. The cam ring 8 acting upon the arm 80 will positively raise the swinging frame 55 after passing this point and prevent the knife cutting farther along the fish. With these bones removed there is nothing to divert the slitting saw and it will follow the center of the abdomen. The rib bones of a 60 fish extend nearly to the center line; therefore, if the slitting saw is diverted but slightly, it will strike these ribs, and as the ribs are resistant to cutting, they will not be cut by the saw, but instead, will be pulled 65 loose from the inner surface of the flanks of the fish, to which they are lightly attached, with the result that this side of the fish presents a frazzled and mussy appearance which detracts very much from its appearance and value. With the bones removed

which lie at the base of the anal fin, there is nothing to divert the slitting saw and it is practically certain of following an exact median course.

In Fig. 10 is shown a cross section of a fish 70 which indicates the position of the rib bones. These do not quite meet at their tips. The broken line Y shows where the cut should be made, exactly central of the fish body, while the line Z shows where the cut is often 75 made by the present apparatus, well to one side of the center. Such a cut tears the ribs loose from the sides and, in addition, produces an overhanging section, 91, of one side which prevents proper entrance of the cleaning apparatus. 80

The bones at the base of the anal fin are shown at 90 in Fig. 11. This figure shows the fins themselves as having been clipped off, or the condition existing when my cutter 85 acts upon it.

What I claim as my invention and desire to cover by Letters Patent is:

1. A cutter for cleaning fish, comprising two sets of cutting blades having their outer 90 cutting ends bent inward or toward each other and together forming the outline of a rounded-edge disk.

2. A cutter for use in cleaning fish, comprising two sets of cutting blades mounted 95 to turn about an axis, said sets being separated axially and having their outer ends curved inward, the blades of the two sets being arranged opposite each other.

3. A cutter for use in cleaning fish, comprising two sets of blades mounted at a slight distance from each other to turn upon a common axis, the outer ends of said blades being bent toward each other and located in opposed relation, the end edges of said 105 blades being inclined to make a V-shaped aperture having its apex rearwardly.

4. A revolving cutter for use in cleaning fish, having cutting edges lying in approximately a tangential plane and inclined to 110 form a V-shaped opening with the large end of the opening forward.

5. A revolving cutter for use in cleaning fish, having cutting edges arranged in pairs, the cutting edges of each pair being located 115 opposite and each consisting of a substantially radial section and an outward extension thereof which curves inward toward the companion blade and then extends across the end edge of the blade, said end edges of 120 the blades being inclined toward each other to form a V-shaped recess having the apex of the recess rearwardly.

6. An attachment for cleaning fish comprising a frame pivoted upon an axis at one 125 side of and parallel the path of movement of the fish, a shaft journaled in said frame and extending over and transversely of the path of movement of the fish, and a cutter carried by the swinging end of said shaft 130

- and having cutting edges outlining a narrow arch.
7. An attachment for fish cleaning machines comprising a frame pivoted upon an axis located at one side of the machine and substantially parallel the path of travel of the fish, a revolving cutter carried by the swinging end of said shaft in position to engage the fish and having separated cutting blades extending substantially radially and then curving at their outer ends toward each other to substantially meet, and means controlled by the passage of the fish to raise the cutter.
- 15 8. An attachment for fish cleaning machines comprising a frame extending transversely of the machine and outside the path of travel of the fish, a supporting pivot axis therefor located at one side of the machine and extending substantially parallel the path of travel of the fish, a revolving cutter carried by the swinging end of said shaft in position to engage the fish, said cutter having cutting edges which extend radially and are separated axially and having extensions which curve inward or toward each other at their outer ends, and a shoe carried by the outer end of said pivoted frame and lying beneath and at each side of the cutters, in position to engage the fish to thereby raise the cutters.
- 35 9. An attachment for fish cleaning machines comprising a pivot shaft secured at one side of the machine and substantially parallel the path of travel of the fish, a frame pivoted upon said shaft, a shaft journaled in this frame and extending transversely of and with one end over the path of travel of the fish, a revolving cutter carried by the swinging end of this shaft in position to engage the fish, shoes carried by the outer or swinging end of the frame in position to be engaged by the fish beneath and at the sides of the cutters, and means for adjusting the position of said shoes.
- 40 10. An attachment for fish cleaning machines comprising a frame pivoted at one side of the machine upon an axis extending substantially parallel the path of travel of the fish at this point, a revolving cutter carried upon this frame in position to engage the fish in its passage, a shoe carried by the frame and engaged by the fish to prevent excessive engagement of the cutter, and positively acting means for raising the cutter at predetermined points.
- 45 11. An attachment for fish cleaning machines comprising a frame pivoted upon an axis at one side of the machine and substantially parallel the path of travel of the fish, a cutter carried by the swinging end of this frame in position to engage the fish, a shoe carried by the frame and engaged by the fish to prevent excessive engagement of the cutter with the fish, a revolving cam, and
- a cam follower carried by the swinging frame and engaging said cam to raise the cutter out of engagement with the fish at predetermined points.
- 55 12. An attachment for fish cleaning machines comprising a cutter having axially separated blades having their outer ends curved inward to a substantial contact, means for supporting and revolving said cutter in position to engage the fish in its passage, a shoe connected with said cutter and adapted to be engaged by the fish to prevent excessive engagement therewith, and means for adjusting the position of the shoe.
- 70 13. An attachment for fish cleaning machines comprising a revolving cutter having axially separated blades with their outer ends curved together and forming a V-shaped recess between their end edges, with the opening of the V forward, means for supporting this cutter to turn in the plane of the path of the fish and to be moved inward and outward relative to the path of travel of the fish, a shoe having supporting connection with the cutter and located beneath and at each side of the cutter in position to engage the fish, and means independent of this shoe to raise the cutter out of engagement at predetermined times.
- 80 14. An attachment for fish cleaning machines comprising a pivot axis supported at one side of the machine and substantially parallel the path of travel of the fish, a frame pivoted thereon and extending transversely from said axis, a shaft journaled in said swinging frame and extending over the path of travel of the fish, a cutter carried by this shaft in position to engage the fish, a pair of bevel gears, one carried by this shaft and the other journaled on the pivot axis, an auxiliary frame pivoted upon the same pivot axis, an auxiliary shaft journaled in said auxiliary frame alongside the pivot axis, a pair of gears, one secured to the auxiliary shaft and the other to the bevel gear which is carried on the pivot axis, means for securing the auxiliary frame in adjusted position, and means for driving the auxiliary shaft.
- 90 15. An attachment for fish cleaning machines comprising a pivot axis supported at one side of and substantially parallel the path of travel of the fish, a frame pivoted upon this axis and extending toward the path of travel of the fish, a shaft journaled in this frame and extending from the pivot axis to and over the path of travel of the fish, a cutter carried by this shaft in position to engage the fish, means for driving said shaft, a cam member rotated in unison with the fish carrying mechanism, and an arm pivoted upon the cutter-carrying frame and engaging said cam member to raise the cutter at predetermined times.
- 95 110 115 120 125 130

16. The combination with a fish cleaning machine having means for engaging and carrying a fish through a predetermined path, and means for slitting the fish, of a 5 rotative cutter placed to act upon the fish in advance of said slitting means and adapted to cut a groove in the body of the fish which groove includes the base of the anal fin.
17. The combination with a fish cleaning 10 machine having means for holding and passing the fish through a predetermined path, and means for slitting the fish, of a revolving cutter placed to act upon the fish in advance

of the slitting mechanism and having cutters which are separated transversely of the fish 15 and with their outer ends converging, and means for controlling the position of said cutter relative to the fish by the passage of the fish.

In testimony whereof I have hereunto 20 affixed my signature this 23d day of October, 1914.

NELS BERNHARD ANDERSON.
